UNITED STATES PATENT OFFICE.

FRED ASHWORTH, OF WENHAM, MASSACHUSETTS, ASSIGNOR TO UNITED SHOE MACHINERY CORPORATION, OF PATERSON, NEW JERSEY, A CORPORATION OF NEW JERSEY.

SORTING MACHINE.

Application filed May 14, 1923. Serial No. 638,897.

To all whom it may concern:

Be it known that I, FRED ASHWORTH, a citizen of the United States, residing at Wenham, in the county of Essex and State 6 of Massachusetts, have invented certain Improvements in Sorting Machines, of which the following description, in connection with the accompanying drawings, is a specification, like reference characters on the drawings indicating like parts in the several figures.

This invention relates to machines for sorting and treating blanks or other articles.

15 It is an object of the invention to remove blanks from an unassorted mass, arrange them with the same surfaces facing uniformly in the same direction, and direct them into blank treating devices, each blank 20 to its proper device having respect to a given dimension of the blank.

The invention contemplates the provision of a hopper for receiving a mass of unassorted blanks having relatively smooth and 25 rough surfaces on opposite sides of each blank, and a conveyor arranged to pass through this mass of blanks to remove from the hopper blanks having their smooth surfaces all facing in the same direction so 30 that the blanks may be properly delivered to a machine designed to operate upon a given surface of each of the blanks.

In the illustrative machine the blanks are 35 operated upon by skiving devices variously adjusted to produce blanks of a given range of thicknesses, and interposed between these devices and the means for arranging the blanks with their smooth surfaces facing uniformly in one direction there is provided 40 means controlled by the thickness dimensions of the blanks for delivering the blanks each to the skiving device set for that thickness of blank.

Other features of the invention relate to 45 a conveyor for receiving the blanks, the said conveyor having a plurality of pockets each with two relatively movable sides designed to clamp each blank in a measuring operation, and subsequently to release the blank 50 when it has arrived at the discharge station proper for blanks of that thickness. Preferably the movable side of the pocket is operated in a positive manner as, for instance, by a toggle so that each blank may

be flattened out to obtain its real thickness 55 unaffected by bent or corrugated portions of the blank. In the construction shown, there is connected to the movable side of the pocket a member which occupies various positions in accordance with differences in 60 the thicknesses of the blanks clamped in the pocket, said member serving to control the breaking of the toggle at the proper place to discharge the blank in accordance with its thickness as determined at the time of 65 the clamping operation.

Other features of the invention and novel combinations of parts will be described in the detailed specification and pointed out more particularly in the appended claims. 70

In the drawings,

Figure 1 is a view in end elevation and partly in section of one embodiment of the invention;

Fig. 2 is a view in front elevation of the 75 machine shown in Fig. 1, parts of the machine being omitted for the sake of clearness;

Fig. 3 is a detail plan view of one of the pockets in the receiving conveyor; 80

Fig. 4 is a view in perspective of the pocket shown in plan in Fig. 3; and

Fig. 5 is a sectional view along the line 5—5 of Fig. 3.

In the illustrative machine there is provided a hopper 10 into which the lifts or other blanks may be dumped in an unassorted mass, the said hopper being open at top and bottom, as will be clear from an inspection of Fig. 1 of the drawings. Passing 90 through the hopper 10 is a conveyor 12 which, in the illustrative construction, comprises two endless chains 14 passing around sprocket wheels 16 carried by suitable shafts 18 rotatably mounted in bearings in 95 the frame of the machine and adapted to be driven through connections (not shown) with any suitable source of power. Mounted upon the chains 14 and pivotally connected thereto, as indicated at 20, (Fig. 2) 100 is a shelf 22 which is of a size to enter the bottom of the hopper 10 and serve as a temporary bottom for the hopper, as well as a blank removing shelf, other shelves 22 being similarly supported on the chains 14 105 and spaced such a distance apart that as one shelf passes upwardly away from the bottom part of the hopper another takes its

place to serve as a support for the blanks in the hopper. In order that each shelf may be maintained in a horizontal position while it serves as a bottom for the hopper, it is 5 provided with an arm 24 rigid therewith and provided at its end with a laterally extending stud carrying a roll 26 adapted to travel in a groove 28 in opposite ends of the hopper 10. This groove 28 is a vertical groove 10 in the lower part of the hopper wall so as to maintain each shelf horizontal during this part of its travel. Subsequently, the groove is inclined inwardly, as indicated at 30, so as to cause a tipping of the shelf for a 15 purpose that will now be described. In operating upon many kinds of blanks it is often desirable to present all of the blanks with a given surface facing uniformly in one direction, since it may be desired to operate 20 upon some given surface or surfaces and to spare a certain other surface of each of the blanks. For instance, in the skiving of heel top lifts, it is desirable to skive the flesh side 25 of the lifts and to preserve the smooth grain surface untouched in the skiving operation. According to this invention the lifts are 30 withdrawn from the hopper 10 with the smooth grain surfaces of the lifts all facing in a given direction and then maintained 35 in this relative position until they have passed into and through the skiving devices. It will be clear that the shelves 22 will remove from the hopper 10 the lifts or other blanks that happen to be in the path of each 40 shelf as it moves upwardly through the mass in the hopper. As each shelf passes from the upper end of the hopper it is gradually tilted at a considerable angle to the horizontal so that those lifts which rest 45 upon the shelf with their smooth faces acting as the supporting face for the blanks or lifts readily slide off and drop back into the hopper, whereas those lifts which rest upon their flesh sides remain upon the shelf 50 and are carried over with their smooth grain surfaces facing upwardly and are discharged into the upper end of the chute 36. This discharge of the lifts from the shelf 22 55 is accomplished through the operation of another part 38 of the slots 28 which are so shaped and arranged as to turn the shelf 22 at such an angle at the proper time that all of the lifts or other blanks slide therefrom into the upper end of the chute. Preferably, 60 and as indicated in Fig. 2, the chute 36 is divided into compartments 40 by partition walls 42 which have pointed upper ends such as to facilitate the entrance of the blanks into individual compartments down 65 which the blanks slide toward the lower end thereof where means is provided for retaining the blanks until the proper time for discharging the same.

The retaining means at the lower end of 70 the compartments 40 in the chute 36 com-

prises, in the construction shown, a pivoted retainer and escapement member for each compartment all operated from a single shaft 44 mounted rotatably in end walls 46 at each side of the chute 36. As shown, 70 each retainer and escapement device comprises a retainer 50 mounted loosely on the shaft 44 extending upwardly therefrom and having its end projecting through a slot in the top cover of the chute 36 in a position to 75 engage with the second blank from the bottom end of the compartment 40. Fixed upon the shaft 44 in close juxtaposition to the retainer 50 is an escapement member 52, the lower end of which is curved inwardly 80 and downwardly so as to extend across the lower outlet of the compartment 40 to retain the lowermost blank in the compartment and to release the same when the shaft 44 is rotated to project the upper ends of 85 the retainer members 50 into contact with the second row of blanks in the compartments 40. For moving the member 50 to blank releasing position there is provided a pin 54 extending laterally from the retainer 90 95 99 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700

In connection with the receiving conveyor 62 there are preferably provided means for receiving the blanks from the chute 36 to maintain them with the smooth grain surfaces facing uniformly in one direction so as to deliver all of the blanks with the grain surface properly related to the skiving devices, and means for insuring that blanks of a given thickness will in each case be fed to the skiving device set for that thickness of blank. Accordingly, the receiving conveyor comprises a plurality of pockets 64 each made up of a relatively stationary wall 66 and a relatively movable wall 68, the latter moving toward the former to clamp the blank B, and thus maintain it with its smooth grain face pointing in the same direction until it has finally been delivered to the proper skiving device. In order that 130

the movable wall 68 of the pocket may be moved toward the relatively stationary wall 66 with sufficient pressure to flatten out the blank against the resistance of corrugated 5 or folded portions of the blank so that the true thickness of the blank may be determined, the said movable wall 68 is preferably operated by a toggle as indicated clearly in Figs. 3, 4 and 5 of the drawings. One 10 link 70 of the toggle is pivoted to the movable wall 68, and its other end received in the forked extremity of the other link 72 which has its other end pivotally connected at 74 to a cross bar 76 which slides upon 15 guideways 78 in the link 80 of the receiving conveyor 62. Interposed between the side 82 of the link 80 and the cross bar 76 is a spring 84 which is relatively heavy but adapted to yield sufficiently to adjust the 20 toggle mechanism to blanks of various thicknesses. Secured to the cross bar 76 preferably at the median point thereof is a headed bolt 86 which extends through an opening in the side 82 of the link 80 and serves 25 to limit the movement of the cross bar 76 in a direction away from the side 82 so that upon breaking the toggle movement is imparted to the movable wall 68 of the pocket 64, the spring 90 serving to move the wall 30 68 to its completely open position and to retain it there until the toggle is again operated to cause a clamping movement of the wall 68 with respect to the relatively stationary wall 66. As shown particularly in 35 Fig. 4, the movable wall 68 is provided with flanges 92 having grooves therein to engage with guideways 94 fixedly mounted upon the side bars of the link 80 in a manner similar to the mounting of the cross bar 76. 40 As each blank drops from the lower end of a compartment 40 into the open pocket adjacent to the lower end thereof, it is received upon a supporting plate 100 (Fig. 2) which is of a length to extend along below all of 45 the pockets at the time positioned at the lower end of the chute 36. As the pockets pass away laterally from the chute 36 the pockets are closed in succession through a stationary cam member 102 (Fig. 2) which 50 is in the path of the knuckle or hinge part of the toggle and serves to force it downwardly until the toggle is in straightened position, as indicated in Fig. 5. Secured to the outer end of the toggle link 72 is a projecting stud 104 adapted to contact with a 55 stop 106 carried by the bar 76 so as to limit the movement of the toggle links in a downward direction, that is, beyond center. At the end of the stud 104 is a roll 108 60 adapted to contact selectively with one of the stationary cam members 110 (Figs. 1 and 2) carried by a bar 111 and each disposed above and in line with one of the skiving devices indicated in general by the 65 reference character 112 (Fig. 2). Refer- ring to Fig. 5 of the drawings, it will be clear that the roll 108 will be positioned nearer the side 82 of the link when a relatively thick blank B is clamped in the pocket 64 and farther from the side 82 when a relatively thin blank is clamped in the pocket. This arrangement is provided for the purpose of discharging a blank of a given thickness to the proper skiving device for operating on blanks of that thickness. Accordingly, the stationary cam blocks 110 bear a definite relation to the plane defined by the side walls 66 of the line of pockets and hence the block 110 opposite the skiving device 113 (Fig. 2) for the thickest blanks will be positioned farthest away from the described plane of the walls 66 while the block 110 opposite the skiving device 115 set for the thinnest blank will be closest to the said plane. In other words, the row of cam blocks 110 defines a line which diverges away from the plane which coincides with the vertical faces of the relatively stationary pocket walls 66, the direction of movement of the receiving 70 conveyor 62 being such as to introduce the pockets at the wider end of the imaginary guideway formed by the line of cam blocks and the plane above described. Hence, the thickest blanks will be dropped into the first skiving device 113 because only the thickest blank will operate to move the roll 108 far enough to the right in Fig. 1 to contact with the cam block 110 at that point. As soon as the roll 108 contacts with a block 110 to co-operate with the latter in breaking the toggle sufficiently to enable the spring 90 to complete the movement of the toggle to the open position of the pocket 64 the blank is discharged into the subjacent skiving device. Preferably a trough-like stationary guide 119 is provided to direct the blanks to the skiving devices as they fall from the pockets of the conveyor. 75

The skiving devices referred to above may be of any of the well-known types or of any desired construction. As shown each skiver consists of a fixed feeding roll 114 (Figs. 1 and 2) and a work-adjustable feed roll 118. Preferably the roll 114 is adjustable with respect to the skiving knife 120 so as to be set at such a distance as to operate properly upon blanks of any given thickness. In other words the setting of the roll and knife with respect to each other determines the thickness of the finished blank. Power for driving both rolls of all the skiving devices may be furnished by connections with the driving chain belt 126 driven from any suitable source of power. 80

Having described my invention, what I claim as new and desire to secure by Letters Patent of the United States is:

1. In a machine of the character described, a hopper, a device arranged to pass through

the hopper from the bottom to the top thereof, and means carried by the device for lifting blanks from the hopper and returning thereto those blanks which have a smooth side in contact with the lifting means.

2. In a machine of the character described, a hopper for containing blanks having relatively smooth and rough surfaces on opposite sides of the blank, a conveyor arranged to pass through the hopper from the bottom to the top thereof, and means carried by the conveyor for sorting out the blanks which have the smooth surface facing one way from those which have the rough surface facing in that direction.

3. In a machine of the character described, a hopper for holding a mass of blanks having relatively smooth and rough surfaces on opposite sides of each blank, and means arranged to pass through the hopper to remove therefrom blanks having one of said surfaces facing in a given direction.

4. In a machine of the character described, a hopper, and means arranged to pass through the hopper from the bottom to the top thereof to lift blanks from the hopper and return thereto those blanks which have a smooth side in contact with the lifting means.

5. In a machine of the character described, a hopper for containing blanks having relatively smooth and rough surfaces on opposite sides thereof, a conveyor arranged to pass through the hopper from bottom to top thereof, and supporting members carried by said conveyor and adapted to remove blanks from the hopper and to return to the hopper those blanks which rest with their smooth surfaces on the supporting members during their passage through the hopper.

6. In a machine of the character described, a hopper for holding a mass of blanks having relatively smooth and rough surfaces on opposite sides thereof, an endless conveyor arranged to pass through the hopper from bottom to top thereof, and shelf members mounted on the conveyor and adapted to remove blanks from the hopper during their upward movement therethrough, said shelf members operating also to return to the hopper those blanks which rest thereon with their smooth surfaces in contact with the shelf member.

7. In a machine of the character described, a hopper for holding a mass of blanks having relatively smooth and rough surfaces on opposite sides thereof, an endless conveyor arranged to pass through the hopper from the bottom to the top thereof, shelf members carried by the conveyor and adapted to take blanks from the hopper during their passage therethrough, and means for tipping each shelf as it passes from the upper end of the hopper to return thereto

those blanks which rest on the shelf member with their smooth surfaces in contact with the shelf member.

8. In a machine of the character described, a hopper for holding a mass of blanks having relatively smooth and rough surfaces on opposite sides thereof, an endless conveyor arranged to pass through the hopper from the bottom to top thereof, shelf members carried by the conveyor and adapted to take blanks from the hopper during their passage therethrough, and a stationary cam for tipping each shelf member as it arrives at the upper end of the hopper so that blanks resting on the shelf members on their smooth surfaces will be returned to the hopper.

9. In a machine of the character described, a hopper having its bottom and top ends open, a conveyor arranged to pass through the hopper from the bottom to the top thereof, and shelf members carried by the conveyor and so spaced from each other that there is always one shelf member serving as a bottom for the hopper, said shelf members being adapted to lift blanks from the hopper, and means for returning certain of the blanks from the shelf members to the hopper.

10. In a machine of the character described, a hopper for holding a mass of blanks having a relatively smooth and rough surface on opposite sides of each blank, means for withdrawing blanks from the hopper with their smooth surfaces facing all in one direction and delivering them with the surfaces facing uniformly in the same direction, and a conveyor for receiving each blank independently of the others to carry it to a discharge station.

11. In a machine of the character described, a hopper for holding a mass of blanks having a relatively smooth and rough surface on opposite sides of each blank, means for withdrawing blanks from the hopper with their smooth surfaces facing all in one direction and delivering them with the surfaces uniformly in the same direction, a receiving conveyor, and measuring clamps on the conveyor for contacting with opposite faces of each blank to measure the thickness of the same and to carry it to a delivery station individual to blanks of that given thickness.

12. In a machine of the character described, a hopper for holding a mass of blanks having a relatively smooth and rough surface on opposite sides of each blank, means for withdrawing blanks from the hopper with their smooth surfaces facing all in one direction and delivering them with the surfaces facing uniformly in the same direction, a receiving conveyor, and positively operated clamping members carried by the conveyor for measuring the

- blanks and thus enabling the conveyor to deliver the blanks at various stations in accordance with the measured thickness of the various blanks.
- 5 13. In a machine of the character described, a hopper for holding a mass of blanks having a relatively smooth and rough surface on opposite sides of each blank, means for withdrawing blanks from the hopper with their smooth surfaces facing all in one direction and delivering them with the surfaces facing uniformly in the same direction, a receiving conveyor, and a plurality of toggle operated clamp members on the conveyor for measuring the thickness of the blanks and for carrying them to various stations in accordance with the thickness of the blanks in the clamps. 70
- 10 14. In a machine of the character described, a hopper for holding a mass of blanks having a relatively smooth and rough surface on opposite sides of each blank, means for withdrawing blanks from the hopper with their smooth surfaces facing all in one direction and delivering them with the surfaces facing uniformly in the same direction, a receiving conveyor, a plurality of clamp members operable to clamp each blank individually after its receipt by the receiving conveyor to measure the thickness of the same, and means for opening the clamp members at the proper discharge station for blanks of the given thickness. 80
- 15 15. In a machine of the character described, a plurality of skiving devices, a hopper for receiving an unassorted mass of blanks having relatively smooth and rough surfaces on opposite sides of each blank, and conveyor means for removing blanks from the hopper and delivering the blanks to the skiving devices with their smooth surfaces all facing in one direction. 85
- 20 16. In a machine of the character described, a plurality of skiving devices each set to skive a blank to a given thickness, and means for selectively delivering to the skiving devices in accordance with the thickness dimension thereof sets of blanks having their smooth surfaces all facing uniformly in a given direction. 90
- 25 17. In a machine of the character described, a plurality of skiving devices set each to skive a blank of a different thickness, a hopper for holding an unassorted mass of blanks having relatively smooth and rough surfaces on opposite sides of each blank, and means for removing blanks from the hopper and delivering them with their smooth surfaces all facing uniformly in a given direction, and each blank of a given thickness to the skiving device set for that thickness. 95
- 30 18. In a machine of the character described, a plurality of skiving devices set each for a different thickness of blank, a hopper for holding a mass of blanks having relatively smooth and rough surfaces on opposite sides of each blank, means for withdrawing from the hopper blanks having their smooth surfaces all facing in a given direction, and means for distributing these blanks each to the skiving device for that thickness of blank. 100
- 35 19. In a machine of the character described, a plurality of skiving devices set each for a different thickness of blank, a hopper for holding a mass of blanks having relatively smooth and rough surfaces on opposite sides of each blank, means for withdrawing from the hopper blanks having their smooth surfaces all facing in a given direction, and means for measuring the thickness of the blanks without disturbing their relations with respect to the facing direction of the smooth surfaces, and delivering the blanks each to the skiving device for that measured thickness. 105
- 40 20. In a machine of the character described, a plurality of skiving devices set each for a different thickness of blank, means for arranging blanks each having a smooth and a rough surface with all the smooth surfaces facing in the same direction, and means controlled by the thickness dimension of the blanks for delivering the blanks each to the skiving device set for that thickness. 110
- 45 21. In a machine of the character described, a plurality of skiving devices set each for a different thickness of blank, a hopper for holding a mass of blanks having relatively smooth and rough surfaces on opposite sides of each blank, a conveyor having shelves for withdrawing from the hopper blanks having their smooth surfaces all facing in a given direction, and positively operated measuring clamps for receiving the blanks indiscriminately and subsequently delivering them selectively each to the skiving device for that particular thickness of blank. 115
- 50 22. In a machine of the character described, a plurality of skiving devices arranged in a row and set to skive blanks of different thicknesses increasing in size progressively from one end of the row to the other, a hopper for holding a mass of loose blanks having each a relatively smooth and rough surface on opposite sides of the blank, means for withdrawing from the hopper a group of blanks having their smooth surfaces all facing uniformly in one direction, and means for measuring the thickness of the blanks and delivering them to the various skiving devices in accordance with the determinations of the measuring means. 120
- 55 23. In a machine of the character described, a plurality of skiving devices arranged in a row and set to skive blanks of different thicknesses increasing in size progressively from one end of the row to the other, a hopper for holding a mass of loose blanks having each a relatively smooth and 125
- 60 65

- rough surface on opposite sides of the blank, a conveyor for withdrawing from the hopper a group of blanks having their smooth surfaces all facing uniformly in one direction, 5 a plurality of pockets into which the group of blanks are received one blank to each pocket with the smooth faces of the blanks still facing all in a given direction, and clamp members for engaging the blanks in the 10 pockets and for delivering the blanks each to the proper skiving device in accordance with the thickness of the clamped blank.
24. In a machine of the character described, a plurality of skiving devices arranged in a row and set to skive blanks of different thicknesses increasing in size progressively from one end of the row to the other, a hopper for holding a mass of loose blanks having each a relatively smooth and 20 rough surface on opposite sides of the blank, a conveyor for withdrawing from the hopper a group of blanks having their smooth surfaces all facing uniformly in one direction, a plurality of pockets into which the 25 group of blanks are received one blank to each pocket with the smooth faces of the blanks still facing all in a given direction, clamp members for engaging the blanks in the pockets to determine the thickness of 30 each blank, and means for tripping the clamp members each at the proper skiving device in accordance with the thickness of the clamped blank.
25. In a machine of the character described, a hopper having its bottom and top ends open, a conveyor arranged to pass through the hopper from the bottom to the top thereof, and shelf members carried by the conveyor and so spaced from each other 35 that there is always one shelf member serving as a bottom for the hopper, said shelf members being adapted to lift blanks from the hopper, and means for tipping each shelf member in succession to return certain of 40 the blanks to the hopper.
26. In a machine of the character described, a hopper for holding a mass of blanks having a relatively smooth and rough surface on opposite sides of each blank, a 45 chute, means for withdrawing blanks from the hopper with their smooth surfaces facing all in one direction and delivering them to the chute with the surfaces facing uniformly in the same direction, a receiving 50 conveyor at the discharge end of the chute, and means in the receiving conveyor for positively clamping each blank independently of the others to carry it to a discharge station.
27. In a machine of the character described, a hopper for holding a mass of blanks having a relatively smooth and rough surface on opposite sides of each blank, a 55 chute, means for withdrawing blanks from the hopper with their smooth surfaces facing

all in one direction and delivering them to the chute with the surfaces facing uniformly in the same direction, a receiving conveyor at the discharge end of the chute, and a measuring clamp for contacting with opposite faces of each blank to measure the thickness of the same and to carry it to a delivery station individual to blanks of that given thickness. 70

28. In a machine of the character described, a hopper for holding a mass of blanks having a relatively smooth and rough surface on opposite sides of each blank, a chute, means for withdrawing blanks from the hopper with their smooth surfaces facing all in one direction and delivering them to the chute with the surfaces facing uniformly in the same direction, a receiving conveyor at the discharge end of the chute, and positively operated clamping members 80 for measuring the blanks received from the chute and for delivering them at stations in accordance with the measured thickness of the various blanks. 85

29. In a machine of the character described, a hopper for holding a mass of blanks having a relatively smooth and rough surface on opposite sides of each blank, a chute, means for withdrawing blanks from the hopper with their smooth surfaces facing all in one direction and delivering them to the chute with the surfaces facing uniformly in the same direction, a receiving conveyor at the discharge end of the chute, and a plurality of toggle operated clamp members 90 for measuring the thickness of the blanks and for carrying them to various stations as determined by the thickness of the blanks in the clamps. 95

30. In a machine of the character described, a hopper for holding a mass of blanks having a relatively smooth and rough surface on opposite sides of each blank, a chute, means for withdrawing blanks from the hopper with their smooth surfaces facing all in one direction and delivering them to the chute with the surfaces facing uniformly in the same direction, a receiving conveyor at the discharge end of the chute, a plurality of clamp members operable to 105 clamp each blank individually after its receipt by the receiving conveyor to measure the thickness of the same, and means for opening the clamp members at the proper discharge station for blanks of the given 110 thickness. 115

31. In a machine of the character described, a plurality of blank treating devices, a hopper for receiving an unassorted mass of blanks having relatively smooth and rough surfaces on opposite sides of each blank, means for removing from the hopper blanks having their smooth surfaces all facing uniformly in the same direction, and means for delivering the blanks to the blank 125 130

treating devices with their smooth surfaces all facing in one direction.

32. In a machine of the character described, a plurality of blank treating devices, a hopper for holding an unassorted mass of blanks having relatively smooth and rough surfaces on opposite sides of each blank, and means for withdrawing from the hopper and delivering to the blank treating devices sets of blanks having their smooth surfaces all facing uniformly in a given direction.

33. In a machine of the character described, a plurality of blank treating devices set each to treat a blank of a different thickness, a hopper for holding an unassorted mass of blanks having relatively smooth and rough surfaces on opposite sides of each blank, a conveyor for removing blanks from the hopper and delivering them with their smooth surfaces all facing uniformly in a given direction, and a conveyor for delivering each blank of a given thickness to the blank treating device set for that thickness.

34. In a machine of the character described, a plurality of skiving devices set each for a different thickness of blank, a hopper for holding a mass of blanks having relatively smooth and rough surfaces on opposite sides of each blank, a conveyor for withdrawing from the hopper blanks having their smooth surfaces all facing in a given direction, and a conveyor for distributing these blanks each to the skiving device for that thickness of blank.

35. In a machine of the character described, a plurality of skiving devices set each for a different thickness of blank, a hopper for holding a mass of blanks having relatively smooth and rough surfaces on opposite sides of each blank, a conveyor for withdrawing from the hopper blanks having their smooth surfaces all facing in a given direction, and a conveyor provided with clamp members to engage the opposite sides of each blank for measuring the thickness of the blanks without disturbing their relations with respect to the facing direction of the smooth surfaces, and for delivering the blanks each to the skiving device for that measured thickness.

36. In a machine of the character described, a plurality of skiving devices set each for a different thickness of blank, a hopper for holding a mass of blanks having relatively smooth and rough surfaces on opposite sides of each blank, means for withdrawing from the hopper blanks having their smooth surfaces all facing in a given direction, and positively operated measuring clamps for engaging the different blanks and subsequently delivering them each to the skiving device for that particular thickness of blank.

37. In a machine of the character described, a plurality of skiving devices arranged in a row and set to skive blanks of different thicknesses increasing in size progressively from one end of the row to the other, a hopper for holding a mass of loose blanks having each a relatively smooth and rough surface on opposite sides of the blank, means for withdrawing from the hopper a group of blanks having their smooth surfaces all facing uniformly in one direction, a receiving conveyor having a plurality of pockets into which the group of blanks are received one blank to each pocket with the smooth faces of the blanks still facing all in a given direction, and means for measuring the thickness of the blanks in the pockets and delivering them to the various skiving devices in accordance with the determinations of the measuring means.

38. In a machine of the character described, a plurality of skiving devices arranged in a row and set to skive blanks of different thicknesses increasing in size progressively from one end of the row to the other, a hopper for holding a mass of loose blanks having each a relatively smooth and rough surface on opposite sides of the blank, means for withdrawing from the hopper a group of blanks having their smooth surfaces all facing uniformly in one direction, a receiving conveyor having a plurality of pockets into which the group of blanks are received one blank to each pocket with the smooth faces of the blanks still facing all in a given direction, and clamp members for engaging the blanks in the pockets and for delivering the blanks each to the proper skiving device in accordance with the thickness of the clamped blank.

39. In a machine of the character described, a plurality of skiving devices arranged in a row and set to skive blanks of different thicknesses increasing in size progressively from one end of the row to the other, a hopper for holding a mass of loose blanks having each a relatively smooth and rough surface on opposite sides of the blank, means for withdrawing from the hopper a group of blanks having their smooth surfaces all facing uniformly in one direction, a receiving conveyor having a plurality of pockets into which the group of blanks are received one blank to each pocket with the smooth faces of the blanks still facing all in a given direction, positively operated clamp members for engaging the blanks in the pockets to determine the thickness of each blank, and stationary cam members for tripping the clamp members each at the proper skiving device in accordance with the thickness of the clamped blank.

40. In a machine of the character described, a conveyor for blanks having a plurality of pockets for receiving the blanks,

said pockets each having a fixed and a movable side between which the blank may be clamped, means for moving the movable side toward and from the fixed side, a member connected to the movable side so that it will occupy different positions in accordance with differences in the thicknesses of the blanks when the latter are clamped one at a time between the movable sides of the pocket, and means controlled by said member for causing the pocket to be opened to release the blank at the station for that thickness of blank.

41. In a machine of the character described, a conveyor for receiving and transporting blanks comprising a pocket adapted to receive one blank at a time, said pocket having a stationary and a movable side for engaging opposite faces of the blank, a toggle for operating the movable side, spring means for backing the toggle so that it may adjust itself to blanks of various thicknesses, a member controlled by the toggle so that it occupies various positions in accordance with differences between successive clamped blanks as to their thickness dimension, and a plurality of members adapted to operate selectively upon the member controlled by the toggle so as to effect the breaking of the toggle at the proper discharge station for the clamped blank.

42. In a machine of the character described, a conveyor for blanks having a plurality of pockets for receiving the blanks,

said pockets each having a fixed and a movable side between which the blank may be clamped, a toggle for moving the movable side, a member connected to the movable side so that it will occupy different positions in accordance with the differences in the thicknesses of the blanks when the latter are clamped one at a time between the relatively movable sides of the pocket, and means controlled by said member for opening the toggle to release the blank at the station for that thickness of blank.

43. In a machine of the character described, a conveyor for receiving and transporting blanks comprising a pocket adapted to receive one blank at a time, said pocket having a stationary and a movable side for engaging opposite faces of the blank, a toggle for operating the movable side, spring means for backing the toggle so that it may adjust itself to blanks of various thicknesses, a member positioned by the toggle so that it occupies various positions in accordance with differences, as to the thickness dimension, in the clamped blanks, and a plurality of members adapted to operate selectively upon the member positioned by the toggle so as to effect the breaking of the toggle at the proper discharge station for the clamped blank.

In testimony whereof I have signed my name to this specification.

FRED ASHWORTH.
